UNITED STATES PATENT OFFICE.

JOSEPH H. JACKSON, OF BIRMINGHAM, ALABAMA.

ROTARY STEAM-ENGINE.

1,217,768.

Specification of Letters Patent. Patented Feb. 27, 1917.

Application filed February 24, 1916. Serial No. 80,218.

To all whom it may concern:

Be it known that I, JOSEPH H. JACKSON, a citizen of the United States, residing at Birmingham, in the county of Jefferson and 5 State of Alabama, have invented a new and useful Rotary Steam-Engine, of which the following is a specification.

The present invention appertains to steam or pressure fluid engines, and aims to provide a novel and improved rotary engine using steam or other motive fluid.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within 20 in the scope of what is claimed without departing from the spirit of the invention.

The invention is illustrated in the accompanying drawings, wherein:-

Figure 1 is a side elevation of the improved engine.

Fig. 2 is a reduced vertical section thereof taken on the line 2—2 of Fig. 3, portions being shown in elevation and portions being broken away.

Fig. 3 is another vertical section taken on the line 3—3 of Fig. 2, portions being shown in elevation.

The engine is carried by a suitable base or frame 1 having the pedestals 2 and 3 provided at their upper ends with the respective bearings 4 and 5, and a wheel or disk 6 disposed adjacent the inner side of the pedestal 2 has a central shaft or spindle 7 attached thereto and journaled through the bearing 4. The disk 6 is provided at that face remote from the pedestal 2 with an outstanding rim 8 defining a square opening or recess 9 and the inwardly facing chordal plane faces 10. The disk 6 acts as a fly wheel 45 when the engine is in operation.

Mounted for rotation within the bearing 5 is a tubular member 11 disposed eccentrically relative to or above the shaft 7. The tubular member 11 is provided with a di- 50 metrical longitudinal partition 12 extending from the inner end to a point outside of the pedestal 3, and said partition provides the passages 13 and 14. The tubular member 11 has an outstanding nipple 15 communicating with the outer end of the passage 55 14. The steam or pressure fluid is supplied

by way of one of said passages, say for example, the passage 13, and the steam is exhausted through the other passage 14. The tubular member 11 is provided adjacent its 60 inner end which projects from the bearing 5 toward the bearing 4, with openings 16 and 17 communicating with the respective passages 13 and 14.

Mounted for rotation upon the inner protruding portion of the tubular member 11 is a rotor 18, and said rotor or drum 18 has a central socket or recess 19 receiving the inner end portion of the member 11. The rotor 18 has a plurality, in this case four, 70 radial cylinders 21 and reduced ports 22 extending from the inner ends of the cylinders to the socket 19 and adapted to move into and out of registration with the openings 16 and 17 of the fluid controlling member 11. 75 A piston 23 is slidable within each cylinder 21 and is provided with one or more packing rings to prevent leakage, and the pistons have outstanding piston rods or stems 24 attached at their outer ends to shoes 25 bearing 80 slidably against the faces 10.

The rotor 18 is preferably provided with packing means 26 surrounding the mouth of the socket 19 and embracing the member 11 to prevent leakage, and a radial handle 27 85 is attached to the member 11 to facilitate the rotation of said member for purpose of reversing the operation of the engine.

The opposite shoes and their pistons are coupled together by yokes, each of which embodies a pair of parallel bars 28 which have their remote ends secured, as at 29, to the outer edges of the opposite shoes 25. The two pairs of bars 28 cross each other, and the bars 28 of each pair are disposed at the 95 opposite sides of the member 11. The outer side of the rotor 18 has outstanding bosses 30 between the bars 28, to assist in guiding said bars, and plates 31 are bolted or otherwise secured to the bosses 30 and overlap the 100 bars 28 to hold them in place adjacent the outer side of the rotor.

The inner side of the rotor 18 is preferably provided with a boss 32 bearing against the disk 6, to hold said disk and rotor in 105 proper operative relation.

In operation, supposing that steam or other pressure fluid is delivered into the passage 13, while the pressure fluid flows from the passage 14 to the atmosphere, the pressure fluid will flow from the passage 13 through the opening 16 into those ports 110 22

which are in registration with said opening 16, and will therefore flow into the corresponding cylinders 21 to force the respective pistons outwardly. The member 11 is so set, as seen in Fig. 2, that when the pistons reach their highest point, their ports 22 come into registration with the opening 16, and as the cylinders move downwardly at the left hand side of Fig. 2, the ports 22 remain in registration with said opening 16, so that steam will flow into the downwardly moving cylinders. As the cylinders reach their lowest point, their ports 22 after having left the opening 16, will be brought into registration with the opening 17, and said ports will remain in registration with the opening 17 during the upward movement of the cylinders at the right hand side of Fig. 2. Due to the eccentric arrangement of the disk 6 and rotor 18, the face 10 at the top will be closer to the center of the rotor than the lowermost face 10, and as the rotor and disk rotate in the direction indicated by the arrow in Fig. 2, the faces 10 gradually move away from the rotor during their downward movement, and gradually move toward the rotor during their upward movement. Consequently, steam being admitted into the downwardly moving cylinders will force the pistons 23 and shoes 25 outwardly, so that the shoes in bearing outwardly against the corresponding faces 10 will impart a turning movement or torque to the disk 6, and due to the sliding bearing of the shoes 25 against the faces 10, the rotor will be rotated with the disk 6. As the shoes move upwardly they are forced inwardly toward the rotor, thereby forcing the corresponding pistons inwardly, to eject the pressure fluid through the passage 14. The shoes 25 slide slightly relative to the faces 10 as the parts rotate, and the opposite shoes being yoked together will operate in unison.

To reverse the engine, the tubular member 11 is rotated through an arc of 180 degrees, 48 which reverses the flow of fluid into and out of the cylinders, so that naturally the rotation of the engine is reversed.

Having thus described the invention, what is claimed as new is:

A fluid pressure engine comprising a frame having a pair of eccentric bearings, a shaft journaled in one bearing, a wheel adjacent the inner side of said bearing secured to said shaft and having an outstanding rim projecting away from said bearing and providing inwardly facing chordal faces, a tubular member extending through the other bearing and having a pair of passages and openings communicating therewith, a rotor having a central socket receiving said tubular member, said rotor having radial cylinders and ports at the inner ends of said cylinders to register with the aforesaid openings, the inner side of said rotor 65 having a boss bearing against the wheel, pistons working within the cylinders and having outstanding rods, shoes attached to the outer ends of said rods and bearing against said faces, crossed slotted yokes terminally 70 attached to the opposite shoes and located at that side of the rotor opposite said wheel, said tubular member extending through the slots of said yokes, that side of the rotor remote from said wheel having outstanding 75 bosses within the slots of said yokes, and plates secured to the last mentioned bosses and overlapping the yokes to hold them in place adjacent to the rotor.

In testimony that I claim the foregoing as 30 my own, I have hereto affixed my signature in the presence of two witnesses.

JOSEPH H. JACKSON.
